REPRODUCTION OF COLOR PHOTOGRAPHIC DESIGNS

Leon Singer, Brooklyn, N. Y.

Application July 29, 1937, Serial No. 156,267

3 Claims. (Cl. 95—2)

My invention relates to a new process of making repeat color designs from color photographs and has among its objects to provide:

Color separation films or transparencies direct from color photographs with the design arranged for repeat or continuous design such as used in textiles, wallpaper, etc.

A novel method or process for reproducing color photographs on textiles.

10 A simplified, direct printing color separation photographic plate suited to cylindrical continuous printing.

While my invention is a method or process the accompanying drawing will serve to illustrate the process and reference characters in the following description are also found on the drawing which illustrates and forms a part of the description.

15 The reproduction of Nature's beautiful designs caught in their natural colors by color photography is made practical by my process. Such designs are modified slightly to make them repeat for continuous printing for instance upon textiles by rearranging the motives.

20 The prohibitive cost of making up a complete repeat color film after which the colors are separated on their several color separation films is unnecessary by the use of my process which provides the color separation films direct from the color photograph and the rearranging of the necessary designs or motives on the film so as to repeat on the color separation films. The moving and rearranging of motive part of design and/or color is a single step and applied to the separation films and not on a master plate or rearrangement.

25 This is made possible by the use of registering indicators or registration points which make the placing of the motives or figures to be moved a matter of easy and positive alignment or registration;

30 To illustrate, the top view of the drawing represents the color photograph; the bottom view is the repeat reproduction in full colors; the views between, the color separation films or negatives enlarged.

35 The rectangle 1 on the colored photograph 2 is to be rearranged and repeated as shown by the numerous somewhat similar rectangles and parts of rectangles 1' on the repeat design at the bottom.

40 It will be seen to make the design repeat that the black object 3 on the right border line 4 must be duplicated on the left border line 5.

45 To facilitate moving the motive 3 at the repeat

line 4 to the repeat line 5 a plurality of indicators 6 are spotted equi-distant from the lines 4 and 5 as well as in fixed relation to the top repeat line 7 and bottom repeat line 8. These indicators appear on the color separation negatives and may be easily removed after the transfer has been made. Likewise any other motive may be transferred to match perfectly the transfer being made on the color separation negative or films. A black object is of course relocated on the black 10 negative film, blue on its respective blue separation film color and as often as there may be a requirement for the rearrangement of motives and also color separation films. Four such plates are shown in the drawing. 15

The distance between line 4 and line 5 is an aliquot part of the circumference of the cylindrical printing roller. For instance the distance may be 5" and the circumference four times 5" or 20".

20 To break up too much uniformity in the repeat design the location of the repeat rectangles are staggered as shown in the bottom figure. The border lines 4 and 5 are exactly half way between the same border lines of the rectangles below. Thus "one half repeats" are required on the upper repeat line 7 and lower repeat line 8.

25 The red object 9 on the repeat line 7 therefore must be repeated at an equal distance for instance at the left side of the rectangle on the bottom repeat line 8 and by the use of the registration points 6 may be located exactly in position on the red color film shown in the second figure from the top.

30 Objects or motives not on repeat or half repeat lines which may be desired to be for any reason removed, replaced or rearranged, may be likewise processed to produce the composite repeat design desired.

35 Thus by careful selection and manipulation photocolor designs may be printed on numerous materials producing effects heretofore impossible and by any ordinary process too expensive to be practical.

40 To facilitate cutting the film up and rearranging the motives, duplicate films and color separation films are used.

45 While the drawing for the purpose of clarity and simplicity shows very simple motives, the usual natural designs are complicated and the color tones and half tones present a great variety. The large motive near the upper right center of the illustration is for instance black, yellow, green, brown, blue and red. Thus the brown center 50 may appear on the black and red separation films. 55

5 The green fringe appears on the blue and yellow color separation films and likewise many combinations of overlying colors may appear on the several color separation films to produce a color not possible on either color separation film separately.

10 The use of ray filters and the screen need not here be discussed as these are commonly used in reproducing printing plates and cylinders.

10 The general process however, of preparing the copper cylinder particularly as applied in repeat printing of color photographs and to my process may help to record the steps desired.

15 The color photograph which may be for instance, flowers or any design or picture is provided with registration points and repeat and half-repeat lines. These points may be small crosses, circles, lines, or any convenient removable or permanent means of registering the motives, objects, etc., which may appear desirable to rearrange, modify or remove to make the repetition of the design possible. Ray filters are then applied to separate the colors on films of which several duplicates are usually made depending on the nature of the design or subject to be rearranged for the repeated design as it will appear when printed on the textile, wall paper, etc. From these color separation films the rearrangement is made, usually by cutting 25 out and adhering such cut-out parts to a new location in relation to the repeat lines and in register with the registration points which appear regardless of color on the color separation films the screen and assembling the several designs 30 with their motives and/or objects then are reproduced on the sensitized metal roll afterward etched or otherwise made ready to print the design in the usual manner.

35 The arrangement of the repeat and half repeat lines may be made in various ways to produce effects less easily detected than the arrangement shown, for instance, other repeat designs may be alternated or several designs may be matched to repeat so that similar designs may 40 be spaced at a sufficient distance from each other to conceal the imaginary repeat lines more effectively.

45 I do not wish to be limited to the details illustrating the application of my process as I may 50 wish to depart therefrom within the scope of the appended claims.

55 I claim:

1. In a process for reproducing color photographic designs, the marking off on an original color design a substantially rectangular portion having certain elements of the design overlap-

ping the border thereof, applying registration marks around said certain elements and around other portions of the border in which said certain elements are to recur in the finished design, making a set of color separation records for each 5 primary color, each set comprising a main record and auxiliary records, cutting out said certain elements in said auxiliary records and affixing them on said other portions of each said main record of the same set by means of said registration marks, forming a number of reproductions of each of the main records so produced, assembling such records to form a repeat design for each color separation and recombining the repeat color separation designs to form a completed color repeat design.

2. In a process for reproducing color photographic designs, the marking off on an original color design a border line setting apart a portion of said original design, said portion having certain elements of the design overlapping the border thereof, applying registration marks around said certain elements and around other portions of the border in which said certain elements are to recur in the finished design, making a set of 10 color separation records for each primary color, each set comprising a main record and auxiliary records, cutting out said certain elements in said auxiliary records and affixing them on said other portions of each said main record of the same set 15 by means of said registration marks, forming a number of reproductions of each of the main records so produced, assembling such records to form a repeat design for each color separation and recombining the repeat color separation designs to form a completed color repeat design.

3. In a process of reproducing parts of a color photograph in a repeated design from an original color photograph having an area thereof set apart and within a certain border, applying registration marks around certain elements in and around said border in which said elements are to recur in the finished design, then making a set of color separation records for each primary color, each set comprising a main record and auxiliary 40 records, removing certain of said elements from said auxiliary records and affixing at least a part of them on said main record by means of said registration marks, forming a number of reproductions of each of said main records so produced, assembling such records to form a repeat 45 color separation and recombining the repeat color separation designs to form the completed color repeat design.

LEON SINGER. 56
